CRUET OR THE LIKE

Theodore M. Reyda, Corning, N.Y., assignor to Corning Glass Works, Corning, N.Y.

Filed Mar. 19, 1973, Ser. No. 342,759

Term of patent 14 years

Int. Cl. D7—06

U.S. Cl. D7—59

Fig. 1

Fig. 2

Fig. 3

Fig. 4

FIG. 1 is a side elevational view of a cruet or the like embodying my new design, with the opposite side being a mirror image.

FIG. 2 is a front elevational view.

FIG. 3 is a rear elevational view.

FIG. 4 is a top plan view.

I claim:

The ornamental design for a cruet or the like, as shown and described.
